COMBINED FOOD DISPLAY CABINET AND EXHAUST VENT

Harold B. Jones, Chicago, Ill., assignor to Leitner Equipment Company, a corporation of Illinois

Filed May 21, 1962, Ser. No. 70,214

Term of patent 7 years

(Cl. D80—11)

Fig. 4

FIG. 2 is a front elevational view thereof;

FIG. 3 is a cross sectional view of the cabinet taken along the line 3—3 of FIG. 1;

FIG. 4 is a rear perspective view thereof taken from the end opposite that shown in FIG. 1; and

FIG. 5 is a bottom plan thereof.

I claim:

The ornamental design for a combined food display cabinet and exhaust vent, substantially as shown.
